MECHANISM FOR OPERATING LOCKS,
LATCHES, AND THE LIKE

José Aurelio Cereda, Buenos Aires, Argentina

Application October 7, 1938, Serial No. 233,863

3 Claims. (Cl. 292—170)

The present invention refers to mechanisms for operating latches used on doors, windows or the like, and which latches are applied independent or in combination with locks of the usual type.

According to this invention, the operation of the latch is effected by direct pressure exerted on a knob that projects laterally from the door or the like, the said knob ending at its internal end with an inclined surface that rests on a member connected to the latch. By means of this disposition, pressing the knob inwardly, the inclined surface forces the member connected to the latch as well as the latch rearwardly, thus unlatching the door or window. A proper spring presses, continuously, to return the latch to its normal or closed position.

This type of knob may be applied at one or both sides of the door or the like, working always upon the same member connected to the latch. Moreover, the knob may be mounted as projecting from a small handle fixed to the door or the like, for facilitating an easy operation thereof.

Besides, means have been also provided for the pushing knob to be stopped in position with a slight rotary movement for stopping the movement of the latch.

For the purpose that the invention be clearly understood and easily carried into practice, the same has been illustrated in the accompanying drawings, in which:

Fig. 1 is a side view of the latch combined with a lock.

Fig. 2 is a perspective detail view of the knob pressing against the latch.

Fig. 3 is a transverse sectional view of the door with the elements applied and in the locking position.

Fig. 4 is a view similar to the former, with the knob in the "pressed" position and the latch moved backwards.

Fig. 5 is a transverse sectional view taken at right angles to the plane of Fig. 3.

Fig. 6 is a fragmentary sectional elevation of tail of the knob and piece fixed to the latch, when the knob has been rotated a quarter of a turn in the operation of stopping the same.

Fig. 7 is a similar view in the position subsequent to the half turn having been accomplished. Referring to these figures there is provided a casing 1 having slidably mounted therein a latch 2 the inner end of which is bifurcated to provide arms 3 and 4 which travel between guides 5 and 6 on the casing; the latch being main-

tained in the position shown in Figure 1 by the action of a spring 7.

Between the ends of arms 3 and 4 there is a small roller 8, freely mounted on a pin 9, upon which rests the inclined surfaces 10 and 10' made, respectively, on the inner ends of the shanks of the knobs 11 and 11'. Said knobs are housed inside tubular handles such as 12, that are applied against the lateral surfaces of the doors, and each of which have an extension 13 provided with threads 14, the threaded extensions being arranged within the corresponding internal cavity 15 provided in the door, and engaged with the adjacent threaded washer 16 thus fixing securely the said handles.

Knobs 11 and 11' have their inner shank portions reduced as at 11, so as to slide in the restricted inner portions of the bores of the tubular handles 12. The outer enlarged portion of the bore of the handle constitutes a chamber 18 for housing spring 19 that continuously presses the knob towards the exterior.

On one of the knobs—that remaining on the internal side of the door or window—there is a slot 20 that receives a stop 21, which both are intended for limiting the movement of the knob and, at the same time, for producing the arrest of the knob.

The operation of the device is very simple. In Figure 3 the latch is shown projecting from the front 22 of the casing and engaged in the keeper 23 provided on the door jamb or the like. When pushing knob 11', its inclined end 10' will press on roller 8, forcing this back and also, obviously, the latch as seen in Figure 4, leaving the door free to be opened. On releasing the knob, spring 19 pushes it back and the latter returns to its normal position by the action of spring 7.

When it is desired to fix the latch in the closed position, it is necessary to rotate the knob, and the steps of rotation have been illustrated in Figures 5, 6 and 7. In Figure 5, the knob is in the normal position; in Figure 6, same has been rotated a quarter of a turn while stop 21 has been displaced within slot 20. In Figure 7 the knob appears turned half a turn and during this rotation it has been necessary to advance the same a little for the purpose that stop 21 may follow angle 24 of the slot and be applied against face 25, so that even when spring 19 is operated, the knob cannot go back, the end thereof remaining behind roller 8, thus locking the latch bolt against movement. On dotted line in Figure 3 can be seen the position of inclined surface 10 after rotation of the knob.

As it has been said before, this latch operating device may be combined with a lock in the form indicated in Figure 1. For that object, the latch is provided with a projection 26, at the rear end of which may advance a piece 27 that operates through the operation of a usual lock device of the simple type or of the drum type, that is applied as shown at 28. Once said piece 27 has been advanced, as illustrated in dotted lines at 27', the latch will be prevented from moving and the door or the like will be kept closed.

Having now particularly described and ascertained the nature of this invention and how same can be carried into practice, I declare that what I claim is:

1. Improvements in mechanisms for operating latches for doors, windows and the like applied independently or in combination with common locks including a casing, a latch slidably mounted therein and having the inner portion bifurcated to provide spaced arms, a roller journaled vertically between the arms, at least one tubular handle fixed to the side of the door and positioned laterally of the casing, a knob having its inner shank portion reduced and slidably and rotatably arranged in the handle and having its extreme inner end inclined for direct engagement with the roller on the latch so that on pushing the rod inwardly the inclined surface contacts the rollers and imparts an inward sliding to the latch to retract the latter, a spring arranged about the shank portion of the knob and within the handle for normally holding the handle in an

extended position, and co-operative means on the handle and inner shank portion of the knob for guiding the shank portion during the half turn of the knob and a locking of the inclined face in the rear of the roller to prevent at times operation of the latch. 5

2. Improvements in mechanisms for operating latches as claimed in claim 1, in which two handle and knob arrangements are provided and located on opposite sides of the door, and the co-operative means being arranged on the handle and knob that are positioned on the inner side of the door. 10

3. Improvements in mechanisms for operating latches in accordance with claim 1 in which the knob is provided with a longitudinal slot which near the inner end of the knob is extended transversely of the knob and is provided with an angular terminal portion, a fixed stop on the body of the handle and engaged in said longitudinal slot for guiding and limiting the movement of the knob, said stop being engageable with the angular terminal of the slot subsequent to passing through the transverse portion of the slot on the turning of the knob to thereby prevent lengthwise movement of the knob, the knob when engaged in the angular terminal portion having its inclined end situated behind the roller fixed to the latch thus also preventing the latch from return movement for opening the door or 20 the like. 25
